LAURENT MOEGLIN, OF TOULOUSE, FRANCE.

AUTOMATIC FEEDING-GOVERNOR FOR STEAM-BOILERS.

1,333,669.

Specification of Letters Patent. Patented Mar. 16, 1920.

Application filed October 16, 1918. Serial No. 258,405.

To all whom it may concern:

Be it known that I, LAURENT MOEGLIN, citizen of the Republic of France, and resident of Toulouse, France, (post-office address 3 Rue Traversière St. Aubin,) have invented a new and useful Automatic Feeding-Governor for Steam-Boilers, which improvements are fully set forth in the following specification:

10 The present invention relates to feed water regulators for steam boilers; and it proposes an improved apparatus of the character indicated by means of which the water level in the boiler is automatically maintained virtually constant, and which omits all such easily worn or damaged devices as spring or counterweight mechanisms, rubber cores, floats, disks and the like, thereby insuring simplicity, efficiency and certainty 15 of operation.

An embodiment of the invention is illustrated in the accompanying drawings, in which:

Figure 1 is a part-sectional side elevation, 25 showing the complete apparatus installed;

Fig. 2 is an enlarged, part-sectional view of the regulator proper and the main valve in the pipe line;

Figs. 3 and 4 are enlarged vertical sectional views of two modified forms of valve-operating connections; and

Fig. 5 is a horizontal section through the operating connection represented in Fig. 4.

Referring more particularly to the drawings, the improved feed water regulator or governor consists primarily of a tubular sheath *a* of cast iron, formed with exterior heat-radiating ribs or fins, in which there is arranged a corrugated thermostatic tube 30 *b* of brass or other readily expandible and contractible metal. This tube *b* is supported at one end by a collar *c* (shown at the top of the tube in Fig. 2, in which the governor or controller is arranged vertically) and carries at its other end a bronze nut *d*, the latter being formed with vertical passages *e* and with a central, threaded opening in which is mounted the threaded end of the stem *f* of the main valve *g*. Immediately below the nut *d* there is provided a return opening or port *m*, which is formed in the top of a valve casing of the usual character, in which valve *g* is mounted. Said casing is included in the main pipe

line for supplying the feed water to the 5 boiler or tank, and is provided at one side with the inlet *h* and at the other side with the outlet *i*, the separating partition between said inlet and outlet having the usual opening providing a seat for the valve. The 6 outlet *i* communicates with the boiler by way of a pipe *j* which terminates adjacent the bottom of the boiler, as shown; the 7 boiler being also equipped with a second pipe *k* which extends upwardly through the 8 casing of the boiler and is connected with the upper end of the brass tube *b*. A portion of this pipe *k* is coiled to form the 9 cooler *r*, and its lower end terminates a slight distance below the normal level of 10 the water in the boiler. Regulating valves 11 *n* and *o* of any suitable type are provided in the pipes *k* and *j*, respectively, to control 12 the flow of water and steam therethrough.

The valve *g*, as best shown in Fig. 2, has 13 rigidly connected to its under side a depending extension or fork, in which is conformably fitted the squared upper portion of a 14 rod *q*, the latter being provided at its lower 15 end with a hand-wheel *p*, said rod passing 16 through a stuffing-box *p'* mounted in the 17 bottom of the valve casing. Rotation of the 18 hand-wheel will, therefore, impart a rotary 19 movement to valve *g*, which latter, during 20 such movement, will be raised or lowered 21 according to the direction of rotation, due to 22 the threaded engagement of its stem *f* in the 23 bronze nut *d*. The purpose of this adjustment 24 will be hereinafter explained.

The operation takes place substantially as 25 follows, reference being had to Figs. 1 and 2: Under normal conditions, valve *g* is closed and the water supply to the boiler is shut off, the water level being as shown. The 26 heat of the boiler will cause a circulation of 27 water through pipe *k* and coil *r* into the 28 brass tube *b*, thence through said tube to nut 29 *d*, and thence through passages *e* and port *m* 30 to the outlet side *i* of the valve casing, whence it is returned through pipe *j* to the 31 boiler. Should the water level sink, the 32 lower end of pipe *k* will be almost immediately uncovered, whereupon the circulation 33 of water will cease. Steam then flows 34 through the course formerly followed by 35 the water, and since its temperature is 36 higher than that of the water, it will exert 37 an expanding action on the brass tube *b* dur-

- ing its passage therethrough, with the result that valve *g* is lowered from its seat. Feed water is then free to flow through the casing into pipe *j* and thence into the boiler.
- 5 When the normal level is again reached, circulation of steam ceases and water-circulation re-commences, the cooler water passing through tube *b* causing a contraction thereof and a consequent raising of valve *g* into closed position, thereby shutting off the feed.

Should it be desired to fill the boiler beyond the normal level, as may be the case after working hours or during a period of rest, this may be readily done by turning the 15 hand-wheel *p* in the proper direction to unseat valve *g*. When the required level is reached, the hand-wheel is turned in the opposite direction so as to close the valve, thereby restoring the apparatus to normal 20 working condition. During the time that the valve is closed, the water fed through the main pipe line by the pump (not shown) is returned to the latter by way of a by-pass connection of some character which is included in the pipe-line at any suitable point 25 but which, since it forms no part of the invention, requires neither illustration nor description.

In the modified construction represented 30 in Fig. 3, the valve stem *f* instead of being immediately connected to nut *d* for actuation thereby, is operated through the intermediary of a link or lever *g'*, which is pivoted at one end at *g''* to a projection or lug 35 on the valve casing and at the other end at *g'''* to an adjustable collar carried by the valve stem, the nut being provided with a screw which is pivoted to the central portion of said lever. The latter will thus be 40 rocked about the pivot *g''* as a fulcrum during the expansion and contraction of the thermostatic tube *b* and, in consequence, will lower or raise the valve. Figs. 4 and 5 show two such levers, arranged in toggle fashion, 45 each lever having an individual screw connection with nut *d*. In all other respects, the operation is identical with that above described.

I claim as my invention:

- 50 1. An automatic feed water regulator for steam boilers, comprising a thermostatic tube; a tubular sheath in which the thermostat tube is axially inclosed; a valve casing connected to the lower end of the sheath 55 and having an inlet and an outlet for the feed water at opposite sides thereof and a port providing communication between said sheath and said outlet; a valve in said casing for controlling communication between 60 the outlet and inlet and having its stem connected with the lower end of the thermostat tube to be raised and lowered consequent upon the expansion and contraction of said tube; a pipe leading from the outlet 65 side of the valve casing to the boiler;

and a separate pipe extending at one end into the boiler to a point slightly below the normal water level and communicating at its other end with the upper end of the thermostat tube, the latter being provided at its 70 lower end with exhaust passages which open into the lower end of the sheath.

2. An automatic feed water regulator for steam boilers, comprising a corrugated brass tube; a tubular cast iron sheath in which the 75 brass tube is axially inclosed, said sheath having exterior heat-radiating fins; a valve casing connected to the lower end of the sheath and having an inlet and an outlet for the feed water at opposite sides thereof 80 and a port providing communication between said sheath and said outlet; a valve in said casing controlling communication between the outlet and inlet and having its stem connected with the lower end of the brass tube to be shifted consequent upon the expansion and contraction of said tube; a pipe leading from the outlet side of the valve casing to the boiler; and a separate pipe extending at one end into the boiler to 85 a point slightly below the normal water level and communicating at its other end with the upper end of the brass tube, the latter being provided at its lower end with exhaust passages which open into the lower 90 end of the sheath.

3. An automatic feed water regulator for steam boilers, comprising a thermostatic tube; a tubular sheath in which the thermostat tube is axially inclosed; a valve casing 100 connected to the lower end of the sheath and having an inlet and an outlet for the feed water at opposite sides thereof and a port providing communication between said sheath and said outlet; a nut carried by the 105 lower end of the thermostat tube and formed with exhaust passages which open into the lower end of the sheath; a valve in said casing to control communication between said inlet and outlet, said valve having its stem connected with said nut to be unseated and seated consequent upon the expansion and contraction of the thermostat tube; a pipe leading from the outlet side of the valve casing to the boiler; and a separate 110 pipe extending at one end into the boiler to a point slightly below the normal water level and communicating at its other end with the upper end of the thermostat tube.

4. An automatic feed water regulator for 120 boilers, comprising a thermostat; a housing therefor; a valve casing connected to the lower end of the housing and having an inlet and an outlet for the feed water at opposite sides thereof and a port providing 125 communication between said housing and said outlet; a valve to control communication between said inlet and outlet having an adjustable threaded connection with said thermostat and adapted to be unseated and 130

seated consequent upon the expansion and contraction thereof, said valve being provided with a depending member; a rod rotatably mounted in the bottom of said casting and projecting outwardly of the same at its lower end, the upper end of said rod having a connection with said depending

member to rotate the latter and thereby raise or lower said valve when the rod is rotated; and means on the projecting lower 10 end of said rod to effect such rotation.

In testimony whereof I have signed this specification.

LAURENT MOEGLIN.
